UNITED STATES PATENT OFFICE.

GRANVILLE H. STALLMAN, OF CHICAGO, ILLINOIS.

SAUSAGE-STUFFING MACHINE.

1,295,809.

Specification of Letters Patent.

Patented Feb. 25, 1919.

Application filed November 8, 1917, Serial No. 200,858. Renewed January 24, 1919. Serial No. 272,971.

To all whom it may concern:

Be it known that I, GRANVILLE H. STALLMAN, a citizen of the United States, residing at Chicago, in the county of Cook and State of Illinois, have invented certain new and useful Improvements in Sausage-Stuffing Machines, of which the following is a specification.

This invention relates to improvements in sausage stuffing machines of the type embodying a cylinder having therein a reciprocating ejector or plunger which operates to eject the filling matter from the cylinder and into the casings.

Heretofore in machines of this character, it has been customary to employ fibrous packing rings with the plunger or ejector, with the result that after the machine has been used for a little while, the animal matter which has been taken up by the packing or that adheres thereto decomposes, resulting not only in a very unsanitary construction, but with the further result that a very disagreeable and obnoxious odor will be emitted therefrom.

To overcome these difficulties and objections and to provide an improved sanitary machine of this character, whereby a metallic packing ring may be employed with the ejector or plunger and which ring is so connected with the plunger or ejector that access may be readily had thereto to remove the same without dismantling the other parts of the ejector or plunger, is one of the objects of the present invention.

A further object is to provide an improved machine of this character in which the plunger or ejector may be moved into a convenient position free of the cylinder so that it can be readily detached from its operating mechanism without dismantling any of the other parts of the machine.

To the attainment of these ends, and the accomplishment of other new and useful objects as will appear, the invention consists in the features of novelty in substantially the construction, combination and arrangement of the several parts hereinafter more fully described and claimed and shown in the accompanying drawings illustrating this invention and in which—

Figure 1 is a vertical longitudinal sectional view of an improved machine of this character, constructed in accordance with the principles of this invention.

Fig. 2 is a detail top plan view of the ejector packing ring.

Fig. 3 is a top plan view of the parts shown in Fig. 1 with the cover of the cylinder closed.

Fig. 4 is a detail view partly in elevation and partly in vertical section, showing one of the fastening devices for the cover.

Fig. 5 is a sectional view taken on line 5—5, Fig. 4.

Referring more particularly to the drawings, the numerals 10 and 11 designate superposed non-communicating cylinders which are supported in any suitable manner, preferably so that the cylinder 11 will extend below the floor line or support 12 while the bottom of the cylinder 10 will be preferably disposed adjacent said floor line. Arranged to reciprocate in the cylinder 11 is a piston embodying two members 13, 14, the bottom member 14 being provided with an open groove 15 extending therearound and the upper member 13 is provided with a flange 16 adapted to project into said groove.

The parts 13, 14 of the piston are secured together for relative movement toward and away from each other by means of suitable fastening devices 17, such as screws which enter threaded portions 18 of the member 14 and are provided with heads 19 which are seated in recesses 20 in the member 13. Packing rings 21 are arranged around the periphery of the member 13 and between the members 13 and 14. With this improved construction, it will be manifest that when pressure is exerted behind the piston in the cylinder 11 to move the same in one direction, the member 14 will be moved toward the member 13 to press the packing rings 21 and force them outwardly against the wall of the cylinder 11 to form a tight joint. Connected with the piston thus formed and preferably to the member 13 is a piston rod 22 which has a threaded engagement with the member. This piston rod passes through a suitable packing box 24 arranged at the bottom of the cylinder 10 and the wall of the cylinder 10 is provided with one or more openings 25 adjacent the packing box so that ready access may be had to the box without dismantling any of the parts of the machine.

A plunger 26 is detachably connected to the other end of the rod 22 and is adapted to reciprocate in the cylinder 10. The rod 22 is of such a length 110

that it is slightly longer than the cylinder 10 so that when the parts are in the position shown in Fig. 1, the plunger 26 will be projected out of the open top 27 of the cylinder 10, so that access may be readily had to the plunger and the same may be readily detached from the piston rod. The upper portion of the ejector 26 is beveled as at 28, for the reception of a metallic packing ring 29.

10 This packing ring is preferably constructed of metal and is split so that the ends 30 thereof which are inclined, will overlap to permit ready expansion and contraction of the packing ring. The packing ring is also 15 provided with a conically shaped opening 31, adapted to receive the tapered portion 28 of the ejector so that the packing ring will rest loosely upon the ejector.

The piston in the cylinder 11 is adapted 20 to be reciprocated in any desired or suitable manner, preferably by means of fluid pressure which is supplied to the cylinder 11 by means of a suitable supply pipe 32 leading from a suitable source. A four-way valve 33 25 is provided for controlling the fluid. Leading from the casing of this valve is a pipe 34 which discharges into the top of the cylinder 11 on one side of the piston therein and this pipe 34 preferably extends into the 30 top of the cylinder through the opening 25 of the cylinder 10. Another pipe 35 leads from the valve casing and discharges into the bottom of the cylinder 11 as at 36 and on the other side of the piston therein. An exhaust 35 pipe 37 also leads from the valve casing.

With this improved construction, it will be manifest that the valve 33 may be adjusted so as to direct the fluid on to one side or the other of the piston in the cylinder 40 11, causing the same to move upwardly or downwardly and the valve is also adapted to form communication between each one of the pipes 34, 35 with the exhaust pipe 37 to permit the fluid on one side of the piston to 45 be discharged. This construction and operation is well known and it is thought that a further specific description of the same is not necessary.

The upper edge of the cylinder 10 surrounding the opening 27 is tapered or deflected as at 38 and the closure 39 for the cylinder is provided with a tapered recess 40 adapted to receive the edge 38 so that when 50 the closure is closed, and drawn tightly in position, the interengaging parts will form a tight joint. The closure is pivotally connected with the casing preferably by means of a pivot 41 which passes through an eccentric sleeve 42, the latter being mounted in 55 suitable bearings 43 and held against rotation therein. When it is desired to adjust the part to take up the wear, all that is necessary is to loosen the eccentric sleeve 44 and adjust the same within its bearing. In 60 order to hold the closure in an open position

and support the same, a suitable stop or shoulder 44 may be provided which is adapted to engage the wall of the cylinder 10.

Any suitable fastening means may be provided for the closure, but preferably a U-shaped ring or bail 45 is provided which engages over a projection 46 on the closure 39. This link is pivotally connected with a pivot pin 47 and the latter is secured to and passes through a suitable eccentric sleeve 48, 75 the pin 47, extending beyond one side of the link 45 for the reception of an operating handle 49 which is secured thereto, and the eccentric sleeve 48 is journaled in a suitable bearing 50.

With this construction, it will be manifest that when the closure is closed, and the link 45 passed over the projection 46 of the closure, the operation of the handle 49 will rotate the eccentric sleeve 48 in its bearing 85 and will draw the link 49 and closure 39 downwardly and the closure will be securely fastened.

The cylinder 10 is provided adjacent its upper portion with discharge outlet openings 90 51 and between which discharge outlet openings, the pipes 34, and 35 are arranged so as to be compact and out of the way of the operators. Connected with these outlets 51 are discharge nozzles 52 on which the sausage 95 casings are slipped. Suitable valves 53 control the discharge of the material through the outlets 51 and into the casings.

With this improved construction, it will be manifest that both of the filling nozzles 100 52 may be employed at the same time either by the same or separate operators, and it will be further manifest that when it is desired to remove the ejector 30 or the packing ring 29 therefrom, all that is necessary is to open 105 the closure 39 and move the ejector so that it will project beyond the top of the cylinder 10, in which position the packing ring 29 may be lifted off of the ejector as it is only loosely held thereon. Furthermore, the ejector may be readily detached from the piston rod 22 without dismantling any of the other parts of the mechanism.

With this improved construction, it will be manifest that a sanitary device is produced and all of the objections incident to the use of fibrous packing on the ejector have been obviated.

By extending the cylinder 11 below the floor line 12, the parts may be compactly arranged and will not necessitate very much floor space, and furthermore, it will permit the other parts to be arranged in a convenient position for the operator.

It is to be understood that while the preferred form of the invention and arrangement of the parts have been herein shown and described, many changes in the details of construction and in the design thereof may be made within the scope of the claims 130

without departing from the spirit of this invention.

What is claimed as new is:

1. A sausage stuffing machine embodying a cylinder having an open top, a closure for the cylinder, said cylinder having a discharge outlet, a plunger head reciprocating in the cylinder, a rod to one end of which the plunger head is detachably connected, a piston exterior of the cylinder and connected with the rod for actuating the plunger, and fluid controlled means for actuating the piston, the said rod being of such a length that when the said closure is open, the plunger head may be projected through the open top to be positioned outside of the cylinder whereby the plunger head may be detached from the rod from the outer face of the plunger.
2. A sausage stuffing machine embodying two superposed cylinders, a piston reciprocable in one of the cylinders, fluid controlled means for reciprocating the piston, a piston rod connected with the piston and extending into the other cylinder, a plunger in the last recited cylinder and connected with the rod, the last recited cylinder being open at its top, and a closure for the cylinder, said cylinder being also provided with a discharge opening, the said piston rod being of such a length that the said plunger may be projected through the open top of the cylinder and moved into a position to extend beyond the cylinder when the said closure is open whereby the plunger may be detached from the rod from the outer face of the plunger.
3. A sausage stuffing machine embodying two superposed cylinders, a piston reciprocable in one of the cylinders, fluid controlled means for reciprocating the piston, a piston rod connected with the piston and extend-

ing into the other cylinder, a plunger on the last recited cylinder and connected with the rod, the last recited cylinder being open at its top, a closure for the cylinder, said cylinder being also provided with a discharge opening, the said piston rod being of such a length that the said plunger may be projected through the open top of the cylinder and moved into a position to extend beyond the cylinder when the said closure is open, whereby the plunger may be detached from the rod from the outer face of the plunger, and a metallic packing ring for the plunger loosely supported by the upper face of the plunger.

4. A sausage stuffing machine embodying two superposed cylinders, a piston reciprocable in one of the cylinders, fluid controlled means for reciprocating the piston, a piston rod connected with the piston and extending into the other cylinder, a plunger in the last recited cylinder and connected with the rod, the last recited cylinder being open at its top, a closure for the cylinder, said cylinder being also provided with a discharge opening, the said piston rod being of such a length that the said plunger may be projected through the open top of the cylinder and moved into a position to extend beyond the cylinder when the said closure is open, whereby the plunger may be detached from the rod from the outer face of the plunger, and a metallic packing for the plunger loosely supported by the upper face of the plunger and forming a portion of the active face of said plunger.

In testimony whereof I have signed my name to this specification, in the presence of two subscribing witnesses, on this 29th day of October, A. D. 1917.

GRANVILLE H. STALLMAN.
